(57) **CLAIM**

The ornamental design for a swaddle band with decorative pattern, as shown and described.

DESCRIPTION

FIG. 1 is a top plan view of a swaddle band with decorative pattern showing our new design;

FIG. 2 is a bottom plan thereof;

FIG. 3 is a top perspective view thereof showing a preparatory stage in wrapping the swaddle band with decorative pattern around an infant;

FIG. 4 is a top perspective view thereof showing the swaddle band wrapped around the infant; and,

FIG. 5 is a bottom perspective view thereof showing the swaddle band with decorative pattern wrapped around the infant.

The broken lines in the drawing views are included to illustrate environment only and form no part of the claimed design.
